UNITED STATES PATENT OFFICE.

JAMES B. ERWIN AND ORLANDO R. ERWIN, OF MILWAUKEE, WISCONSIN.

FOAM-GENERATING APPARATUS.

1,214,661.

Specification of Letters Patent. Patented Feb. 6, 1917.

Application filed March 4, 1916. Serial No. 82,048.

To all whom it may concern:

Be it known that we, JAMES B. ERWIN and ORLANDO R. ERWIN, citizens of the United States, residing at the city of Milwaukee, county of Milwaukee, and State of Wisconsin, have invented new and useful Improvements in Foam-Generating Apparatus, of which the following is a specification.

10 Our invention relates to apparatus for and process of generating and forcibly discharging foam for extinguishing fires, and it pertains to that class of fire extinguishers which are adapted to be operated by inverting.

15 The primary object of this invention is to provide the simplest and most efficient method and apparatus for utilizing the expansive force of foam to drive one or more 20 of the liquids which form the foam from their containing receptacles into a foam generating chamber to be therein thoroughly mixed to form foam previous to its forcible ejection upon the fire, substantially as fast 25 as generated.

Our invention is further explained by reference to the accompanying drawings, in which—

Figure 1 is a vertical sectional view of one 30 form of our extinguisher in its normal upright position charged ready for use. Fig. 2 shows the device shown in Fig. 1 in its inverted discharging position, showing the commingling of the foam producing liquids 35 and the consequent formation and ejection of the foam, and Fig. 3 is a modified form of the device shown in Figs. 1 and 2 in its inverted discharging position.

Like parts are identified by the same reference characters throughout the several views.

1 represents a substantially closed receptacle, closed at its lower end by the head 2, and at its upper end by the cap 3 together 45 with the plate 4. The cap 3 is preferably removably screw-threaded at 5 to the receptacle 1 upon the collar 6 thereof in the ordinary manner, and the plate 4 is preferably removably supported upon a flange 7 provided 50 therefor at the lower edge of said collar, the cap having inwardly extending projections 25 overlying the said plate 4 for retaining the plate seated upon the said flange. The cap 3 is preferably dome-shaped which together with the plate 4 forms a substantially closed foam

generating chamber 8, the plate 4 having its upper face dished as at 26 forming the bottom of the said generating chamber. The cap 3 is further provided with a discharge 60 spout 9 for foam to which a hose (not shown) may be attached to facilitate playing the foam upon a fire.

10 is a wheel shaped handle rigidly connected to the cap 3 with which the extinguisher may be transported, and upon which it is adapted to stand when inverted. An acid receptacle 11 is preferably rigidly supported from the plate 4 in the aperture 12 therefor provided, and a discharge duct 13 70 is provided in said acid-receptacle 11 to permit the acid 14 to be discharged into said foam generating chamber 8, only when said extinguisher is inverted. A discharge outlet 15 is also provided in the plate 4, through 75 which the solution 16 located in the receptacle 1 escapes into said foam generating chamber 8, when the extinguisher is inverted. The plate 4 is further provided with an open duct 17 for foam which duct 80 17 is rigidly supported in an aperture 18 therefor in said plate 4, and said duct extends from thence approximately to the bottom of said receptacle 1, reference being had to Fig. 1.

To charge the device shown in Fig. 1 the cap 3 is first unscrewed and removed from the receptacle 1, when the plate or partition 4 is free to be removed for washing and refilling the receptacle 1. The receptacle 1 is 90 then filled nearly full with a suitable foam producing solution 16 such as an alkali, when the plate 4, together with the depending acid receptacle 11 and foam duct 17, is inserted back in place in said receptacle 1, 95 the plate 4 being supported upon the annular flange 7, as before stated. A second foam producing liquid 14 (preferably sulfuric acid) is then funneled into the receptacle 11 through its outlet 13, until the same 100 is nearly filled, when the cap 3 is screwed back tight in place upon the collar 6 of the receptacle 1 when the extinguisher is ready for use.

To discharge the device shown in Fig. 1, 105 the same has simply to be inverted as shown in Fig. 2, when the solution 16 will flow through duct 15 in plate 4 of its own gravity (at first) into the foam generating chamber 8 immediately below, likewise the liquid 110 14 in the receptacle 11 will simultaneously be discharged through the outlet 13 into

said foam generating chamber 8, wherein the two foam generating liquids will be commingled and form foam by chemical reaction, a portion of which foam will, by 5 its own expansion flow up said open duct 17 and collect in the upper end of said receptacle 1 above the solution level 20 thereof, and therein create a pressure upon said solution which combined with the gravity 10 thereof will cause said solution 16 to be forcibly ejected into said foam generating chamber. A thorough commingling of the liquids 14 and 16 is thereby effected previous to the discharge of the resultant foam which 15 is ejected through the discharge duct 9.

The device shown in Fig. 3 is in all respects similar to that shown in Figs. 1 and 2, except that a duct 22 is provided in the acid receptacle 11' by means of which duct a 20 portion of the foam generated in the chamber 8 is forced upwardly by its own expansion to the space above the liquid level 30 in said acid receptacle whereby a pressure is exerted upon such liquid which assisted by 25 gravity causes its ejection into said chamber 8 under the pressure generated therein. The said duct 22 is supported from its upper end, reference being had to Fig. 3, from the boss 23 in the receptacle 11', screw-threaded 30 or otherwise connected therewith in any convenient manner. The lower end of said duct 22 preferably extends through and slightly beyond the discharge outlet 13' and loosely fits therein as shown.

35 Foam entering the lower open end 23' of said duct 22 passes up therethrough to the upper end when it escapes through a plurality of holes 24, 24 therein to the space above the liquid in said receptacle 22, said liquid 40 being forcibly ejected therefrom through the discharge outlet 13' therefor in the lower end of said receptacle 22.

Having thus described our invention what we claim as new and desire to secure by Letters Patent, is:—

1. A foam generator comprising a receptacle having a threaded collar at its open end and provided with an annular inwardly-extending flange at the base of the said collar, 50 a perforated plate arranged within the said collar upon the said flange and having a dished upper face, a cap secured upon the said collar and having inwardly extending projections restrainingly overlying the said 55 plate providing a generating chamber with-

in the said cap and dished portion of the plate, a discharge member carried by the said cap, and a container carried by the said plate having a discharge duct within the said generating chamber.

2. A receptacle for foam generating fluid having a threaded collar at its open end and provided with an annular inwardly-extending flange at the base of the said collar, a 60 perforated plate arranged within the said collar upon the said flange and having a dished upper face, a cap secured upon the said collar and having inwardly-extending projections restrainingly overlying the said plate providing a generating chamber with- 65 in the said cap and dished portion of the plate, a discharge member carried by the said cap, a foam conducting pipe carried by the said plate extending within the said receptacle and communicating with the generating chamber, an acid container carried by the said plate having a closed end arranged within the receptacle and an open end positioned within the said chamber, and a foam 70 conducting pipe carried by the inner end of the said container communicating with the interior thereof and extending axially outwardly of the container outlet within the said chamber.

3. A foam generating fire extinguisher 85 adapted to be operated by inversion comprising a storing receptacle for a foam producing solution, a perforated plate upon the said receptacle, a dome-shaped cap upon the receptacle overlying the marginal points of 90 the said plate and providing a foam generating chamber therein, an acid receptacle carried by the said plate adapted to discharge acid into said chamber only when the device is inverted, a foam conducting ex- 95 pulsion means for the contents of the said acid receptacle communicating with the interior thereof adjacent its bottom and with the said generating chamber, a foam conducting expelling means for said solution receptacle communicating between the said chamber and spaced above the solution level when the device is inverted.

In testimony whereof we affix our signatures in the presence of two witnesses.

JAMES B. ERWIN.

ORLANDO R. ERWIN.
